EXPLOSIVELY ACTUATED TOOL

Sidney H. Broughton and Virginius Robert Erickson, Portland, Oreg., assignors, by mesne assignments, to Omark Industries, Inc., a corporation of Oregon
 Original application May 17, 1954, Ser. No. 430,288, now Patent No. 2,773,259, dated Dec. 11, 1956. Divided and this application Nov. 5, 1956, Ser. No. 628,945
 7 Claims. (Cl. 1—44.5)

This invention relates to devices or tools which employ an explosive charge for forcibly imbedding fastening elements, such as bolts, studs and the like, in masonry or in other hard or semi-hard surfaces and substances. This application is a division of our copending application Serial No. 430,288, filed May 17, 1954, now Patent No. 2,773,259 granted December 11, 1956.

The use of explosively driven projectiles in the form of bolts and studs for the purpose of providing anchoring or fastening elements on such structures as concrete walls, for example, is well known, and various devices or tools have been developed for this purpose. Such tools employ explosively driven projectiles and are provided with firing mechanism generally of more or less familiar type.

An explosively actuated tool of the general type with which this invention is concerned may be used for imbedding elements into walls or other bodies of different density. If, for example, the density of the work surface is considerably less than that of ordinary concrete, the use of the same explosively driven projectiles suitable for ordinary concrete would be likely to result in the projectile being driven too far into the work and thus being driven in so far that it would be of no use as a fastening element.

Accordingly, another object of the invention is to provide an explosively actuated tool in which the force with which a given explosively driven projectile is driven into the work can be adjusted and modified to some extent in a simple and practical manner whenever this is necessary.

While generally the work in which the projectile or fastening element is required to be imbedded has a continuous flat surface and the muzzle end of the gun barrel of the tool is held against such surface and approximately perpendicular thereto, it is sometimes necessary for a fastening element to be secured in a recessed portion of a surface. A further object of the present invention is to provide an improved explosively actuated tool in which the gun barrel muzzle can be held in a recess while the protective means, previously mentioned, at the same time can be held against the outer face of the work around the recess in order to afford the desired protection against any particles which may be dislodged in the recess in the operation of the tool and which particles otherwise might be forcibly ejected from the recess and thus constitute a dangerous hazard to the operator or to any other persons standing nearby.

An additional object of the invention is to provide an improved explosively actuated tool having a gun barrel and associated suitable firing mechanism so arranged that the tool cannot be fired unless the barrel is pressed against the portion of the work in which the projectile is to be imbedded; and further with the firing mechanism so controlled that it cannot then be fired by the operator unless the operator releases a safety control with one hand while he actuates the trigger with the other hand, thus making impossible any inadvertent firing or discharging of the tool.

A still further object of the invention is to provide an explosively actuated tool which will accomplish the previously indicated objects, and which must be opened each time for loading, the opening requiring special ma-

2

nipulation on the part of the operator, and from which a previously fired cartridge will be automatically ejected upon the opening of the tool.

The construction and manner of operation of our improved explosively actuated tool and the means by which these mentioned objects and other advantages are achieved will be briefly described and explained with reference to the accompanying drawings.

In the drawings:

10 FIGURE 1 is a sectional elevation taken longitudinally along the approximate center line of the device showing the device loaded with a projectile to be explosively driven, but with the device shown prior to being set for firing;

15 FIGURE 2 is a similar sectional elevation showing the device set for firing;

20 FIGURE 3 is an end elevation taken from the right of FIGURE 1 showing the front face of the safety pad attachment, which safety pad is placed against the work in the ordinary use of the device;

25 FIGURE 4 is a vertical sectional view taken on line 4—4 of FIGURE 1;

30 FIGURE 5 is a fragmentary vertical sectional view taken along the longitudinal section of the muzzle end of the gun barrel of the device and through the safety pad, and illustrates the manner in which the safety pad will accommodate a slight tilting of the barrel with respect to the work surface during the firing of the device;

35 FIGURE 6 is a fragmentary vertical sectional view corresponding in part to the left hand portion of FIGURE 2, but showing the position of the trigger and related members of the firing mechanism when the device is being fired;

40 FIGURE 7 is a fragmentary vertical section taken on line 7—7 of FIGURE 2;

FIGURE 8 is a corresponding vertical fragmentary section taken on line 8—8 of FIGURE 6;

45 FIGURE 9 is a fragmentary horizontal sectional view taken on line 9—9 of FIGURE 7 and looking upwardly as indicated by the arrows;

FIGURE 10 is a perspective view of the entire device viewed from the opposite side;

50 FIGURE 11 is a fragmentary horizontal sectional view taken on line 11—11 of FIGURE 6;

FIGURE 12 is a fragmentary side elevation of the rear or handle end of the device with a portion broken away and showing the breech end of the gun barrel, and also illustrating the device as partly opened preparatory to the ejection of the empty cartridge and the reloading of the device;

55 FIGURE 13 is a similar fragmentary side elevation corresponding to FIGURE 12, with a portion similarly broken away and shown in section, but showing the device fully opened and the empty fired cartridge in the process of being ejected;

FIGURE 14 is a fragmentary vertical sectional view taken on line 14—14 of FIGURES 1 and 2;

60 FIGURE 15 is a fragmentary side elevation, with portion broken away, taken from the left of FIGURE 14;

FIGURE 16 is a fragmentary horizontal section taken on line 16—16 of FIGURE 15; and

65 FIGURE 17 is a vertical sectional view corresponding in part to FIGURES 1 and 2, but showing the muzzle portion of the gun barrel pressed into extended position beyond the safety pad for special use in discharging a projectile into a recess in the work.

Referring first to FIGURES 1, 2 and 10, the housing for the device is made up of three separate portions, namely, the handle portion 10, the intermediate portion 11, and a front end sleeve portion 12. The gun barrel 13 of the device extends through housing portions 11 and 12 and both of such housing portions are longitudinally

slidable to a limited extent relative to the gun barrel. The muzzle end of the gun barrel preferably has a removable tip 14, which tip has a bore coinciding with the gun barrel bore and which tip also has two or more radially extending exhaust gas ports 15 located at the approximate relative distance from the end of the tip 14 shown in FIGURES 1 and 2. Although the tip 14 could constitute an integral part of the muzzle end of the gun barrel we prefer to have the tip removable so that it can be easily replaced in the event of damage or excessive wear in the course of the use of the device.

The outer end of the sleeve portion 12 of the housing has an integral eccentric circular flange 16. A square shaped housing or shield 17, having an off-center circular opening of slightly less diameter than that of the flange 16, is rotatably mounted on the circular flange 16 by means of a circular disc 16A, attached to the flange 16 by suitable rivets (not shown) and having lugs 16B (FIGURE 4) which engage the underside of the housing 17 around the circular opening in the housing. The housing 17 is formed with a wall 17' extending around all four sides. Due to the fact that the circular flange 16, on which the housing 17 is mounted, is eccentric with respect to the gun barrel 13 and also due to the fact that the housing 17 is eccentric with respect to the circular flange 16, the housing 17 can be rotated with respect to the gun barrel muzzle so as to bring the gun barrel muzzle either close to an edge of the housing 17 or at the center of the housing 17. FIGURES 3 and 4 show the gun barrel muzzle at the center of the housing 17. The reason for having the housing 17 movable and adjustable with respect to the gun barrel channel will be explained later.

A square plate 18 (FIGURES 1, 2 and 5), slightly smaller than the housing 17, is mounted in the housing 17 by means of four mounting pins 19, located at the four corners of the plate 18, which pins extend freely through slightly larger apertures in the top of the housing 17. These pins terminate in enlarged heads in order to prevent the plate 18 from dropping away from the housing 17. A coil spring 20 is carried on each pin 19 and held under slight compression between the plate 18 and the housing 17. The plate 18 has an off-center circular opening corresponding to and in registration with the off-center circular opening in the housing 17.

A second plate 21, which is circular and the diameter of which is less than the diameter of the circular opening in the plate 18, is located in the opening, and this second plate is similarly mounted in the housing 17 by similar pins 22 which extend through the flange 16 and disc 16A. Coil springs 23 are similarly mounted on the pins 22.

A pad 24, preferably of resilient material such as rubber, covers the outer face of the plate 18 and is secured to the surface of the plate. A similar pad 25 covers the second plate 21 and is secured to the second plate. The pad 24 is preferably formed with a rim shoulder 24' at its periphery and the pad 25 is similarly formed preferably with a rim shoulder 25' at its periphery.

The breech end of the gun barrel 13 is secured to a barrel block 26 on which the housing portion 11 of the device is slidable to a limited extent. A sleeve 27, mounted on the central portion of the gun barrel, has one end held in a recess in the block barrel 26 and the opposite end held in engagement with a ring 28, the ring 28 in turn being held in place on the gun barrel by a locking ring 29. The sleeve 27 extends through a wall partition 30 which is secured within the housing portion 11, and the wall 30 slides on the sleeve 27 when the housing portion 11 is moved with respect to the gun barrel. Similarly, the front housing sleeve portion 12 of the device is slidable on the ring 28. A coil spring 31, held under compression between the wall 30 and the ring 28, normally holds the housing portion 11 in the position shown in FIGURE 1, with reference to the gun

barrel, but permits the housing portion 11 to be moved forwardly with respect to the gun barrel against the force of spring 31 (thus towards the right as viewed in FIGURE 1), to the position illustrated in FIGURE 2. A shoulder 27' on the sleeve 27 limits the forward movement of the housing assembly with respect to the gun barrel by engaging the wall 30.

The front end sleeve portion 12 of the housing and a ring band 60 secured in the front of the housing portion 11 are relatively slidable with respect to each other. The ring band is firmly held in the end of the housing portion 11 by a latch member 61, which, in turn, engages a locking notch in the ring 60. The inner end of the sleeve portion 12 has a rim flange 62 which engages the ring 60 when the sleeve portion 12 is in the normal position shown in FIGURE 1. A spring 64, extending around the muzzle portion of the gun barrel, is held under compression between the ring 28 on the gun barrel and the disc 16A which is secured to the flange 16 of the sleeve portion 12. A spring-controlled lever lock 63 ordinarily limits the extent to which the housing portion 11 can be moved forwardly with respect to sleeve portion 12.

As will be later explained, before the device can be fired the housing assembly must be thrust forwardly against the force of springs 31 and 64 from the position of FIGURE 1 to the position of FIGURE 2. This is done by placing the muzzle end of the gun barrel (or the end of the tip 14 when the gun barrel is equipped with the removable tip) against the work W (FIGURE 2) and pressing the device against the work sufficiently to cause the housing portion 11, and with it the handle portion 10, to be pushed forwardly the necessary distance for bringing the device into position for firing. While this is done the pads 24 and 25 on the spring-mounted plates 18 and 21 will be held pressed against the work as illustrated in FIGURE 2. In such position the pads 24 and 25 with their surrounding housing 17 will act as a protection to the operator and to any bystanders against any fragments or particles which may be dislodged from the work around the gun barrel muzzle as a result of the firing of the device, for any such dislodged fragments will strike against the pads 24 or 25 and be restrained by the pads. The rim shoulders 24' and 25' on the forward face of the pads furthermore will prevent any possibility of such fragments being discharged laterally between the pads and the work surface. The pads 24 and 25 with their rim shoulders, are held against the surface of the work not only by their springs 20 and 23 but, during the firing of the device, some of the high velocity air and gases will pass through the ports 15 at the muzzle end of the gun barrel and will momentarily cause pressure to be exerted on the rear face of the plates 18 and 21 within the housing 17 and thus exert additional force to keep the pads 24 and 25 firmly pressed against the work as the projectile is driven into the work.

Even though the device is held by the operator at the time of the firing of the same, in such way that the gun barrel is inadvertently tilted slightly out of the desired position of perpendicularity with respect to the work surface, and thus if the gun barrel should be held in the manner illustrated in FIGURE 5, the plates 18 and 21 and their pads 24 and 25, due to the fact that the pins 19 and 22 are loosely mounted in the housing 17 and flange 16 respectively, will nevertheless accommodate themselves to any such slight inclination of the gun barrel with respect to the work surface and thus continue to perform their function of preventing any fragments from flying away from the work surface.

Ordinarily the housing or shield 17 and the protecting pad 24 are arranged as shown in FIGURES 3 and 4, thus with the gun barrel centrally located with respect to the pad and its surrounding housing. However, there may be occasions when the projectile is required to be driven into the work adjacent a wall extending at right angles to the work. In such case, the housing 17, and with it the plate

18 and pad 24, upon being rotated 180° with respect to the gun barrel and the flange 16, will cause one outside edge of the pad 24 and housing to be brought close to the gun barrel, thus enabling the gun barrel to be positioned in close proximity to the intersection of such wall with the work surface.

A breech block 32 (FIGURES 1, 2, 6, 7, 8, 14 and 16) is positioned in the handle portion 10 of the housing assembly, and the handle portion is slidable to a limited extent on the breech block 32. This breech block is U-shaped in horizontal cross section, having two separated extending portions 32', shaped in the form of cylindrical segments, which are positioned within extended side portions 10' (FIGURES 13 and 16) of the housing portion 10. A lug 33 (FIGURES 12 and 13) extends outwardly from one of these portions 32' of the breech block and extends through a slot 34 in the corresponding housing extension 10'. The engagement of the lug 33 with the ends of the slot 34 limits the travel of the handle portion 10 with respect to the breech block 32. The two extending portions 32' of the breech block 32 are positioned respectively adjacent the flat sides of the barrel block 26 at the breech end of the gun barrel (FIGURES 13, 14 and 16), and these portions 32', and with them the block 32 and handle 10, are pivotally mounted on the barrel block 26 by means of the pivot pin 35 (FIGURES 1, 2, 6 and 12) by which the portions 32' are connected to the barrel block 26.

A rod 36 (FIGURES 12 and 13) extends longitudinally through the barrel block 26 and is slidable therein and is also slidably mounted in the housing wall 30. This rod 36 has an enlarged head which is located within a recessed chamber 37 in the housing portion 11 and engages a coil spring 38. The opposite end of this rod 36 is arranged for engagement with a recess 39 (FIGURE 12) in the middle body portion of the breech block 32. The arrangement is such that the rod 36 prevents any pivoting of the breech block 32 and handle portion 10 with respect to the barrel block 26 and housing portion 11 until the handle portion 10 of the housing assembly and the portion 11 are first pulled a maximum distance apart from each other, which results in thrusting the housing portion 11 forwardly with respect to the gun barrel and pulling the handle portion 10, and with it the barrel block 26 and gun barrel as far as possible in the opposite direction, as illustrated in FIGURE 12. When this is done the handle portion of the device can then be pivoted with respect to the rest of the device and thereby bring the device into the opened position illustrated in FIGURE 13.

A cartridge ejector plate 40 (FIGURES 1, 13, 14, 15 and 16), normally seated in a corresponding recess in the rear face of the barrel block 26, is mounted on a rod 41 which is slidable in a bore in the barrel block 26. A pin 42, secured to the rod 41 and extending at right angles from the rod 41, slides in a slot 43 in the barrel block 26 and extends a slight distance beyond the side face of the barrel block 26 as shown in FIGURE 16. A coil spring 44' engages the pin 42 and normally holds the pin 42 and rod 41 and ejector plate 40 in the position illustrated in FIGURES 15 and 16.

An arm 44 (FIGURES 13, 15 and 16), located in a recess 45 on the face of one of the portions 32' of the breech block 32 and opposite the slot 43, which arm 44 is pivotally supported in the recess 45 for limited movement, is so shaped and arranged (as shown best in FIGURES 13 and 15) that, when the device is opened and the handle portion 10 including breech block 32 is swung down (in counter-clockwise direction, as viewed in FIGURE 15, and in clockwise direction, as viewed in FIGURE 13), the arm 44 will normally engage the pin 42, pushing the pin 42, and with it the rod 41 and ejector plate 40 against the force of spring 44' and thrusting the plate 40 into the ejecting position shown in FIGURE 13. However, as the handle portion is rotated downwardly

still further, the arm 44 then slips out of engagement with the pin 42 and the plate 40 will be returned to its normal position by the force of the spring 44'. The ejector plate 40 is formed with a curved shoulder along its bottom edge which is concentric with the gun barrel channel and which is adapted for engagement with the rim of the head of the cartridge C as shown in FIGURES 1 and 13.

The breech block 32 (FIGURES 1, 2 and 6) has a bore to accommodate the firing pin 46 so as to enable the firing pin to strike the cap on the head of the cartridge C when the firing pin is released. The firing pin 46 is slidably mounted in a stationary wall 47 in the handle portion 10 and is moved by the force of a compression spring 48. A sear plate 49 is slideable up and down to a limited extent on the breech block 32.

The firing pin 46 has a reduced diameter portion at its forward end forming a shoulder on the firing pin. The sear plate 49 (see also FIGURES 7 and 8) has an aperture 49A, the diameter of which corresponds to the firing pin diameter behind the shoulder, and this sear plate also has a slot 49B extending above the aperture 49A the width of which slot corresponds to the smaller firing pin diameter ahead of the shoulder. When the sear plate is in the normal low position of FIGURES 1 and 7 it holds the firing pin back from engagement with the cartridge, but when raised to the firing position of FIGURES 6 and 8, the sear plate releases the firing pin. A spring 50 holds the sear plate normally in the low, firing-pin-engaging position. A trigger 51 (FIGURES 1, 2 and 6) is so positioned as to enable the sear plate 49 to be raised when the breech block 32 occupies the rear position of FIGURES 2 and 6.

In order to prevent any inadvertent actuation of the trigger 51, even when the members of the device are in firing position, a trigger safety locking lever 52 is provided (FIGURES 2, 6, 9, 10 and 13) which is pivotally mounted in an outside recess in the housing portion 10 and which has an outwardly extending finger push knob 53 (FIGURES 9 and 13) at its forward end. The opposite or rear end of the lever 52 extends inwardly into the device sufficiently to rest on the top of the trigger, as shown in FIGURES 1 and 2, and prevents actuation of the trigger when in such position. The lever 52 is pivotally mounted on the pin 52' (FIGURE 9) and a spring, indicated at 53', holds the lever 52 in its normal position (shown in full lines in FIGURE 9), in engagement with the trigger but permits the lever to be moved out of trigger-engaging position to the position shown in dotted lines in FIG. 9 by finger pressure on the knob 53. Thus, in order to fire the device not only must the muzzle of the gun barrel be pressed against the work and the device held thrust against the work, but the knob 53 must also be pressed inwardly before the trigger can be pulled. Due to the location of the knob 53, both hands of the operator are required to be used in order to fire the device. Consequently any inadvertent firing of the device is quite impossible.

The inner portion of the gun barrel 13 is formed with a longitudinally-extending groove 54 (FIGURES 1 and 2) on its outside wall. Ports 55 and 56 at the ends of this groove respectively connect with the gun barrel channel. The groove 54 is formed into a separate channel by the encompassing walls of the sleeve 27 and barrel block 26. Thus the resulting channel groove 54, due to its connection at each end with the main gun barrel channel, constitutes an auxiliary bore or gas escape passage. An adjustable screw 57, controlling passage through the port 55, is capable of allowing some of the discharge gas from the discharging cartridge C to pass through this auxiliary bore, and consequently the adjusting of this screw 57 regulates the amount of discharge gas which will pass through the auxiliary bore. The screw 57 can, of course, close off the auxiliary bore entirely.

The head 58 of this adjustment screw 57 (FIGURES

1, 2 and 6) is located in a recess 59 in the bottom of the barrel block 26 (see also FIGURE 11) and is accessible for adjustment when the device is in fully opened position. Preferably the head 58 of the adjusting screw and the cavity wall are provided with some indicia markings so that the screw 57 can be set for a predetermined accurate adjustment and in this way provide for accurate control of the passage of gas through the port 55 and thus through the auxiliary bore.

As will be evident from FIGURES 1 and 2, the purpose of this auxiliary bore or gas escape passage 54 is to enable a portion of the explosive gases, discharged upon the firing of the cartridge C, to pass through the auxiliary bore, when desired, in order to reduce the amount of driving force exerted upon the projectile by the discharged gases released from the fired cartridge. By bleeding off some of the discharged gases behind the fired projectile and delivering them subsequently back into the main bore of the gun barrel (which gases will be delivered back into the gun barrel bore in advance of the projectile due to the inertia in the projectile, when first acted upon by the explosive gases) the force with which the projectile is driven into the work can be modified. This is an important feature since it enables identical explosively driven projectiles to be used on different densities of material without having the projectile driven too far into the work surface if the density of the work happens to be less than that for which such explosively driven projectile was originally intended.

Preparatory to operating the device the handle portion 10 and the portion 11 of the housing are pulled a maximum distance apart into the relative position shown in FIGURE 12. The handle portion 10 is then swung downwardly to the position illustrated in FIGURE 13 causing any previously fired cartridge to be ejected, and, as the handle portion 10 swings down slightly further, the ejector plate 40 returns to normal position, enabling a cartridge and projectile to be placed in the breech end of the gun barrel. The handle portion 10 is then moved back into normal position and the handle portion 10 and portion 11 of the housing are allowed to come together. The device will now be in the normal position illustrated in FIGURE 1 and loaded for firing.

In the firing operation the muzzle end of the gun barrel is placed against the surface into which the projectile is to be discharged and the handle portion 10, and with it the housing portion 11, are thrust forwardly on the gun barrel against the force of the springs 64 and 31, and also against the force of the springs 20 and 23 which bear against the plates 18 and 21 respectively. The sear plate 49 holds the firing pin 46 against forward movement so that the firing pin spring is also compressed. This brings the device into the position illustrated in FIGURE 2 in which the lower portion of the sear plate is above the trigger 51. While the device is held in this position, the operator presses the knob 53 (FIGURE 9) inwardly to release the trigger locking lever 52, and then presses the trigger 51. The pressing of the freed trigger raises the sear plate 49 (FIGURE 4) and releases the firing pin 46, causing the firing pin, under the impetus provided by the spring 48, to strike the head of the cartridge and cause the explosively-driven projectile to be discharged.

Occasionally it may be desired to drive the projectile or fastening element into the work at some point which is recessed from the remaining work surface. If the muzzle end of the gun barrel were held spaced from the bottom of each recess it would then be spaced from the actual surface to be pierced by the projectile. This would prevent the firing of our improved device, but even if firing were possible with the gun muzzle end spaced from the surface to be pierced the results would not be satisfactory. Therefore, we have made provision so that the gun barrel muzzle in such case may extend for considerable distance beyond the protective pads 24 and 25 and the housing 17.

The inner end of the housing portion or sleeve 12 has

a rim flange 62 which is normally engaged by the spring-controlled locking lever 63 when the device is set for firing. However, release of the locking lever 63, which is done by pressing the opposite end of the lever against the force of spring 65, enables the rest of the housing assembly, together with the gun barrel, to be thrust forwardly against the force of spring 64 to some such position as illustrated in FIGURE 17. In this position this muzzle end of the gun barrel will extend a considerable distance beyond the protective pads 24 and 25.

Thus, by releasing the locking lever 63, the muzzle tip of the gun barrel can be caused to engage the inner wall of a recess in the work while at the same time the protection pads 24 and 25 are held by spring force against the main surface of the work around such recess and will continue to perform that function of protecting the operator and bystanders against any fragments which may be dislodged by the impact of the projectile or discharged gases.

Several minor modifications would be possible in our improved device without departing from the principle and scope of our invention. The device in the form as described and illustrated has been found to be very satisfactory in practice and we regard this as the preferred construction, but it is not our intention to limit our invention otherwise than as set forth in the claims.

We claim:

1. In a stud driving tool, a rear handle portion including a breech block comprising a yoke member having spaced apart yoke sections extending forwardly from said handle portion, a front barrel containing portion including a barrel block positioned between said yoke sections, a barrel mounted in and extending through said barrel block and between said yoke sections, a pivot pin connecting said yoke sections and said barrel block to provide for pivotal movement of said portions to expose the breech end of said barrel and interlock means normally preventing relative pivoting movement between said portions, parts of said portions being connected to have relative sliding movement in a direction longitudinally of said barrel away from each other, resilient means urging said parts toward each other to engage said interlock means, said interlock means being released by relative movement of said parts away from each other.
2. In an explosively actuated tool including a handle portion and a barrel containing portion, a breech block carried by said handle portion, a gun barrel carried by said barrel containing portion, a connection between said portions providing for relative pivotal movement of said portions about an axis transverse to the axis of said barrel to expose the breech end of said barrel, locking means preventing said relative pivotal movement, said handle portion being slidable relative to said barrel containing portion in a direction longitudinally of said barrel, resilient means urging said handle portion toward said barrel containing portion to engage said locking means, said locking means being releasable by movement of said handle portion away from a portion of said barrel containing portion.
3. In an explosively actuated tool, a housing assembly including a handle portion, an intermediate portion and a forward end portion, a gun barrel in said intermediate portion and forward end portion of said housing assembly, said housing assembly being mounted for limited slidable movement with respect to said gun barrel and said handle portion and intermediate portion being relatively movable in a direction longitudinally of said barrel away from each other, the breech end of said gun barrel adapted to receive a cartridge, a barrel block secured on the breech end of said gun barrel and located in said intermediate portion of said housing assembly, a breech block adjacent said barrel block and located in said handle portion of said housing assembly, said handle portion being slidable to a limited extent on said breech block, said breech block being hingedly connected with said barrel block, whereby said handle portion with said breech block may be swung

to open position with respect to said barrel block and intermediate portion of said housing assembly, resilient means urging said handle portion and intermediate portion toward each other, and a hinge lock engageable by relative movement of said handle portion and intermediate portion toward each other for preventing said handle portion from being swung to open position, said hinge lock being releasable by relative movement of said handle portion and said intermediate portion in a direction away from each other.

4. In a device for driving projectile fastening elements into a solid work surface, a housing assembly comprising a handle portion, an intermediate portion and a forward end portion, a gun barrel in said intermediate portion and forward end portion of said housing assembly, said housing assembly being mounted for limited slidable movement with respect to said gun barrel and said handle portion and intermediate portion being relatively movable in a direction longitudinally of said barrel away from each other, spring means holding said housing assembly in normal position with respect to said gun barrel and urging said handle portion and intermediate portion toward each other, the breech end of said gun barrel adapted to receive a cartridge, a barrel block secured on the breech end of said gun barrel and located in said intermediate portion of said housing assembly, a breech block adjacent said barrel block and located in said handle portion of said housing assembly, said handle portion being slidable to a limited extent on said breech block, said breech block being hingedly connected with said barrel block whereby said handle portion with said breech block may be swung to open position with respect to said barrel block and intermediate portion of said housing assembly to expose the breech end of said barrel, and a hinge lock preventing said handle portion from being swung to open position, said hinge lock being engageable by relative movement of said handle portion and said intermediate portion toward each other and releasable by relative movement of said handle portion and said intermediate portion in a direction away from each other.

5. In a stud driving tool a rear handle portion including a breech block comprising a yoke member having spaced apart yoke sections extending forwardly from said handle portion, a front portion containing a barrel and including a barrel block positioned between said yoke sections, a pivot pin connecting said yoke sections and said barrel block to provide for pivotal movement of said portions to expose the breech end of said barrel and interlock means normally preventing relative pivoting movement between said portions, parts of said portions being connected to have relative sliding movement in a direction longitudinally of each barrel away from each other, resilient means urging said parts toward each other to engage said interlock means and said interlock means being released by relative movement of said parts away from each other.

6. In an explosively actuated tool including a handle portion and a barrel portion, a breech block carried by said handle portion, a gun barrel carried by said barrel portion and having a breech end normally closed by said breech block, a connection between said portions providing for movement of said breech end of said barrel in a

direction laterally of said breech block to expose the breech end of said barrel, interlock means normally preventing said movement, parts of said handle and barrel portions having relative sliding movement in a direction longitudinally of said barrel away from each other, resilient means urging said handle and barrel portions toward each other to engage said interlock means and said interlock means being released by said relative movement of said parts away from each other.

7. An explosively actuated stud driving tool comprising a front portion including a barrel block and a barrel having its rear end extending through said barrel block, and a rear portion including a handle part and a breech block in the form of an integral yoke member having yoke portions extending forwardly and embracing said barrel block, the axis of said barrel and said end of said barrel extending between said yoke portions, a pivot pin connecting said breech block to said barrel block for relative pivotal movement of said portions between a closed position and an open position of said portions, said rear portion having a part thereof in alignment with the longitudinal axis of said barrel when said portions are in said closed position relative to each other, said pivot pin being spaced laterally from said longitudinal axis and extending perpendicularly to said longitudinal axis, said front portion also including a barrel housing assembly slidably mounted on said barrel for movement longitudinally of said barrel, a spring positioned between said housing assembly and said barrel to urge said housing assembly toward said rear portion of said tool with respect to said barrel, a locking element carried by said housing assembly and interengaging with said rear portion to lock said rear portion to said front portion against said pivotal movement when said front and rear portions are in said closed position relative to each other, said locking element being releasable from said rear portion upon sliding movement of said housing assembly longitudinally on said barrel to compress said spring to thereby enable pivotal movement of said front and rear portions relative to each other to said open position.
